(57) **CLAIM**

The ornamental design for a root-cutting garden tool, as shown and described.

DESCRIPTION

FIG. 1 is an isometric view of the invention;

FIG. 2 is top view of the invention;

FIG. 3 is a bottom view of the invention;

FIG. 4 is a side view of the invention;

FIG. 5 is a front view of the invention; and,

FIG. 6 is a rear view of the invention.

The broken lines in the drawings illustrate portions of the root-cutting garden tool and form no part of the claimed design.
